Inventor,
Harold M. Gusdorf,
By *Joseph A. Minturn*
Attorney.

UNITED STATES PATENT OFFICE.

HAROLD M. GUSDORF, OF INDIANAPOLIS, INDIANA.

DRIVE-BELT MATERIAL.

Application filed April 19, 1920. Serial No. 375,160.

To all whom it may concern:

Be it known that I, HAROLD M. GUSDORF, a citizen of the United States, residing at Indianapolis, in the county of Marion and State of Indiana, have invented a new and useful Drive-Belt Material, of which the following is a specification.

The object of this invention is to provide a belt material for pulleys either side of which will bend around a pulley without puckering, thereby securing the maximum belt contact with any pulley to be driven.

My object is in other respects to increase the elasticity, efficiency and durability of the belt.

I accomplish the above and other objects which will hereinafter appear, by the means illustrated in the accompanying drawing, in which:—

Fig. 1, is a perspective view and longitudinal section of a belt illustrating my invention more or less diagrammatically. Fig. 2, is an under side view of Fig. 1, showing the pits in plan, and Fig. 3, is a cross section of a belt made out of pig skin in which the essential characteristics are preserved.

Like characters of reference indicate like parts in the several views of the drawing.

The body of the belt preferably has sinuous and wave-like warp fibers 6 running lengthwise of the belt, the waves being substantially transverse to the thickness of the belt, and weft fibers 7 on one side of the belt interwoven with the bends of the warp to firmly anchor and tie those portions together and produce a comparatively close unyielding surface on that side. Other weft strands 8 run somewhat nearer straight and parallel with the surface, passing through waves of the warp, and make that side of the belt considerably more open and loose in its texture.

A body-material conforming as closely as practicable to the above, has indent 9 on the firm side of the belt to increase the facility for bending around small pulleys without puckering that surface. The resulting closure of the indents adds to the

contacting surface of the belt and therefore to its pulling efficiency. Larger indentations or pits 10 are in the opposite or looser side of the belt for easier bending in that direction and also to act as vacuum cups to prevent slipping.

I have found that pig skin taken from along the back of the animal has substantially the above described wavy warp fibers and weft fibers nearer straight, and that it has wrinkles in the outer or firm side of the hide and grease pits on the loose inner side; all of which natural features are preserved and amplified by proper care to increase the thickness of the leather instead of making it thinner in tanning, whereby greater pliability, elasticity, and resiliency are developed than would otherwise be possible, and whereby a belt made from pig skin so tanned is superior in durability and pulling efficiency to that made from any other leather. By actual test such a belt made from pig skin leather in accordance with this invention has developed a tensile strength of more than 4,580 pounds to the square inch of end surface.

A belt made out of pin skin leather in which the natural fiber and grain have been preserved may be in single or in double thickness; and in the latter case the pitted sides may be cemented together; or a pitted side cemented to a more solid side; or the two more solid sides cemented together; which will afford a variety of product to suit many different requirements.

Having thus fully described my invention, what I claim as new and wish to secure by Letters Patent of the United States, is—

1. As a new article of manufacture, a belt for the transmission of power formed from pig-skin leather.

2. A belt for the transmission of power the pulley-contacting side of which is pig-skin leather.

In witness whereof I have hereunto affixed my signature at Indianapolis, Indiana, this 23rd day of March, 1920.

HAROLD M. GUSDORF.
